CLAIM

The ornamental design for the snuff box, as shown and
described.

DESCRIPTION

FIG. 1 is a front exploded perspective view of the snuff box. The rear perspective view is the same as the front perspective view. The snuff box includes a lid placed over a container. Certain features on the interior of the container may form part of the claimed design.

FIG. 2 is a front exploded view of the snuff box of FIG. 1 rotated approximately 45° from left to right. The rear view is the same as the front view.

FIG. 3 is a right side exploded view of the snuff box of FIG. 1 rotated approximately 45° from left to right. The left side view is the same as the right side view.

FIG. 4 is an overhead view of the snuff box of FIG. 1 rotated approximately 45° from left to right.

FIG. 5 is an underside view of a snuff box of FIG. 1 rotated approximately 45° from left to right; and,

FIG. 6 is perspective view of a snuff box of FIG. 1. The view in FIG. 6 results from the snuff box of FIG. 1 being flipped over and rotated about 90° from left to right.

In general, any broken line illustration of environmental structure in the drawing forms no part of the design sought to be patented.
